UNITED STATES PATENT OFFICE.

BERNARD MORGAN, OF NEWPORT, RHODE ISLAND, ASSIGNOR TO CLARENCE E. NORTON,
OF GUILFORD, CONNECTICUT.

LEAF-SPRING-SEPARATING DEVICE.

1,168,735.

Specification of Letters Patent.

Patented Jan. 18, 1916.

Application filed January 14, 1914. Serial No. 811,964.

To all whom it may concern:

Be it known that I, BERNARD MORGAN, a subject of the King of Great Britain, residing at Newport, in the county of Newport and State of Rhode Island, have invented a new and useful Improvement in Leaf-Spring-Separating Devices, of which the following is a specification.

This invention relates to certain new and useful improvements in leaf spring separating devices, and relates more particularly to a device of the character specified which is employed to separate the leaves of a leaf spring so as to permit same to be oiled.

The primary object of the invention is to provide a device for the purpose mentioned, which enables the leaves of the spring to be easily and quickly separated, with the expenditure of minimum force, and by use of but one hand of the operator, thereby leaving the other hand of the operator free so as to enable same to apply the lubricant.

Further, and other objects of the invention are to provide a simple and economical structure, which involves a minimum of parts.

In the drawings—Figure 1 is a perspective view of the invention, showing the same in use. Fig. 2 is a perspective view of the invention, showing the two parts in folded position so as to store in a small space in a tool kit or chest, and Fig. 3 is an inverted perspective view of the invention.

The invention involves the provision of a bar 1 which is disposed transversely of the spring, and which has an inturned knife-edge wedge shaped end portion 2 formed by bending the end of the bar over upon itself. The opposite end of the bar is formed with an enlarged or outwardly projecting part 3, which extends on the same side of the bar as the wedge shaped portion 2. Eccentrically pivoted to the enlargement 3 is the circular head 4 of an operating member having a handle 5, the head 4 being beveled to a knife edge so as to easily enter between two of the leaves of the spring. The pivoting of the head may be accomplished by providing an integral pin 6 on the enlargement 3, which pin extends through an eccentrically located aperture provided for the reception thereof in the head 4, the pin being secured relative to the head 4 by a cotter pin 7 or its equivalent, which cotter pin may seat on a washer 8.

In operation, the end 2 is first placed in position to enter in the space between two leaves of the spring at one side of the latter, as depicted in Fig. 1 of the drawings, whereupon the head 3 is rotated so as to engage the said two leaves of the spring at the sides of the latter opposite to those which the end 2 engages, after which the operator turns the head 4 by applying force to the handle 5, so as to cause the end 2 and the beveled edge of the head 4 to simultaneously approach each other, and to act as wedges which separate the two leaves of the spring in an obvious manner. After separation, as the device is self locking, the operator need not retain pressure on the handle, but may apply the lubricant. The parts when not in use may be folded or moved to the position indicated in Fig. 2 of the drawings in which the device occupies small space and can be conveniently stored in a tool kit or case.

Having thus described my invention, I claim as new and desire to secure by Letters Patent:—

1. In a device of the type set forth, a bar having a knife-edge wedge shaped inturned end, the opposite end of the bar having an enlargement which extends on the same side of the bar with said inturned end, a pin extending outwardly from the enlargement, and an operating member having a knife edged circular head eccentrically mounted on the pin and having a handle which extends outwardly from the head.

2. In combination with a bar having an inturned wedge shaped end portion to engage between two of the leaves of a spring, wedge shaped means on the opposite end of the bar to engage between said leaves on the opposite sides thereof, and means whereby said means may be moved toward the inturned end portion of the bar.

3. In combination with wedge shaped means to engage between two of the leaves of a spring at one side thereof, a rotatable member having a wedge-shaped portion connected to the said means and being for engagement between said two leaves at the opposite sides thereof.

4. In a spring separating device, a frame including two upright arms, a wedge member carried by one arm facing the other arm

and a swinging wedge member carried by the other arm and facing the first mentioned wedge.

5. In a spring separating device, a frame including two upright arms, a wedge member carried by one arm facing the other arm, and a movable wedge member carried by the other arm and facing the first mentioned wedge, said movable wedge member being pivoted intermediate its ends.

6. In a spring separating device, a frame including two upright arms, a wedge member carried by one arm facing the other arm and a movable wedge member carried by the other arm and facing the first mentioned wedge, said movable wedge member being mounted to swing, with means to permit said movable wedge member to be reversed, whereby it may be swung into operative position either by a right hand or left hand movement.

7. In a spring separating device, a rigid yoke, a wedge rigidly carried by one arm thereof and facing the other arm, a lever pivotally mounted on the other arm and including a separating handle at one end and a wedge at the other end, the last mentioned

wedge being located in substantially the same plane as the first mentioned wedge, and being arranged to swing in said plane, whereby said wedges may be moved relatively toward and from each other.

8. In a spring separating device, a frame including two arms, a wedge member carried by one of said arms and facing the other, a swinging wedge member having a curved edge, said wedge member being pivoted on the other arm and facing the first mentioned wedge.

9. In a spring separating device, a frame including two arms, a wedge member carried by one of said arms and facing the other, a swinging wedge member having a curved edge, said wedge member being pivoted on the other arm and facing the first mentioned wedge, the upper and lower surfaces of both of said wedges being substantially flat.

In testimony whereof I have signed my name to this specification in the presence of two subscribing witnesses.

BERNARD MORGAN.
